DINNER PLATE OR SIMILAR ARTICLE

Edward M. Otis, Syracuse, N.Y., assignor to Syracuse China Corporation, Syracuse, N.Y., a corporation of New York

Filed Apr. 13, 1966, Ser. No. 1,867

Term of patent 14 years

(Cl. D44—15)

FIG. 2

FIG. 1 is an enlarged scale fragmentary plan view of a dinner plate or similar article showing my new design, with a repeat unit shown between the dashed lines; and

FIG. 2 is a plan view of a dinner plate of conventional configuration showing the path of repeat of the pattern.

I claim:

The ornamental design for a dinner plate or similar article, as shown and described.
